ORNAMENTAL WINDOW LOCK

William L. Fitzpatrick, Philadelphia, Pa.

Application December 18, 1941, Serial No. 423,547

1 Claim. (Cl. 292—150)

The invention relates to a window sash fastener, and it consists in the constructions, arrangements, and combinations herein described and claimed.

It is a particular object of the invention to provide a sash fastener of simplicity and efficiency in operation and manufacture and in addition provide means for display of an ornamental design.

It is a further object of the invention to provide an ornamental design for windows which is incorporated in a window sash fastener, a portion of which functions to lock a pair of window sash frames against movement, yet readily movable to release the frames for movement.

Additional objects, advantages and features of invention will be apparent from the following description, considered in conjunction with the accompanying drawing, wherein

Figure 1 is a fragmentary front elevation of a pair of sash frames having my fastener incorporated thereon.

Figure 2 is a vertical cross section on the line 2—2 of Figure 1.

Figure 3 is a perspective view of the fastener.

Figure 4 is a perspective view of the latch plate.

Attention is first invited to Figure 2 of the drawing, wherein there is shown a portion of window frame 10 having a pair of cooperable sliding sash frames 11 and 12, all of which may be conventional construction.

As may be seen in Figure 3, my fastener comprises a pair of base members 13 and 14 of substantially rectangular form, the end portions of which are provided with respective ears 15 apertured to receive fastening screws or the like 16. The base member 13 is secured to the lower rail of the upper sash 11, while the base member 14 is fixed to the upper rail of the lower sash 12 and are so positioned as to present mutually adjacent longitudinal edges in close abutting relation when the sash members are in closed position.

The base member 14 has integrally formed therewith and extended laterally from the front longitudinal edge, an extension 17 of lesser thickness than the member 14. Medially of the extension 17 and extending transversely of the base member 14 a rectangular opening 18 is formed adapted to register with a similar opening 19 formed transversely of the base member 13, but stopping short of the outer longitudinal edge of the base. A recess 18' is formed in the extension 17 aligned with the opening 19.

Slidably mounted in the opening 18 and recess

18' there is a latch plate 20 of a length less than the combined lengths of the openings 18 and 19, the outer end of the plate being provided with a right angularly extended portion 21, which functions as an operating handle for sliding the plate as well as a stop to limit inward and outward movement of the plate as may be readily seen from Figure 2.

The plate 20 is provided with an opening 22 adapted to register with an opening 23 extending vertically of the base 13 for a purpose now to be explained.

Upon the upper face of the base member 13 there is secured an upstanding ornamental object 24, this in the present instance being shown in the form of a sail-boat, although various ornamental frames may be employed such as a lighthouse, fish, birds, and the like. A vertical bore 25 is formed through the ornament 24 aligned with the opening 23 of the base 13, and slidable within the bore 25, there is a rod 26 which terminates in an ornamental grip 27. The rod 26 is of a length so as to stop inwardly of the bottom of the base 13 when engaged through the openings 22 and 23.

As shown in Figure 2, the device is in closed or latched position, the latch plate 20 being extended across the sash rails 11 and 12, and the rod 26 extended through the apertures 22 and 23 of the latch plate and base member respectively. In such position both sash frames are securely held against sliding movements. However, when it is desired to open a window it is only necessary to grasp the grip 27 and pull upwardly upon the rod so as to move it from engagement with the aperture 22 of the latch plate. The latch plate 20 may now be drawn outwardly as indicated in dotted lines in Figure 2, so as to fully disengage the slot 19 of the base 13, in which position either of the sash frames may be moved. To again latch the window, it is only necessary to close them, raise the rod 26 and slide the latch plate 20 to its innermost position which will align the openings 22 and 23. The rod 26 is now moved into the aligned openings and the latching operation is completed.

While I have shown and described a preferred form of the invention, this is by way of illustration only, and I consider as my own all such modifications in construction as fairly fall within the scope of the appended claim.

I claim:

In a sash lock, a pair of base members, each being mounted on respective sash frames and positioned to register when the sash frames are

in closed position, one of said base members having a transverse opening, the other of said base members having a medial rearward extension provided with a recess aligned with a transverse opening formed in said base member, said recess stopping short of the extremity of the extension to form a latch stop member, the transverse openings of the base members being in alignment in the closed positions of the sash frames, a latch plate slidable in said recess and through the aligned transverse openings of the base members so as to extend across the sash frames, said latch

5
10
plate having an opening adapted to register with a vertically extended opening in the first named base member, an upright element on said first base member having a bore in registry with the vertically extended bore of the first named base member, a rod slidable through the bore for engagement through aligned openings of the first named base member and the latch plate, and said latch plate having a right angular extension forming a gripping means for moving the latch plate.

WILLIAM L. FITZPATRICK.
